United States Patent Office

Des. 216,254
Patented Dec. 9, 1969

216,254

UTILITY TRAILER

Gasper V. DeBella, San Mateo, Calif., assignor to Cal-West Electric, Inc., a corporation of California

Filed May 16, 1969, Ser. No. 17,186

Term of patent 14 years

Int. Cl. D12—10

U.S. Cl. D14—3

FIG-1

FIG. 2

FIG. 3

FIG-4

FIG-5

FIGURE 1 is a plan of a utility trailer showing my new design;

FIGURE 2 is a left side elevation of the utility trailer;

FIGURE 3 is a front elevation of the utility trailer;

FIGURE 4 is a right side elevation of the utility trailer; and

FIGURE 5 is a rear elevation of the utility trailer.

I claim:

The ornamental design for a utility trailer, as shown.
